TYPEWRITING MACHINE

Filed April 15, 1927

INVENTOR.
Richard v. Reppert

UNITED STATES PATENT OFFICE

RICHARD V. REPPERT, OF HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed April 15, 1927. Serial No. 183,999.

This invention relates to an improvement in typewriting machines and more particularly to the key mechanism thereof and has for its main object to provide a noiselessly operable key mechanism, whereby printing is accomplished by an instantaneous pressure instead of an impact.

A further object is to provide a type member positioning mechanism, whereby the operation of a key moves the respective type member to printing position, adjacent to the platen.

Another object is to provide a universal pressure printing member subject to actuation by any one of the keys and adapted to engage and press against the platen for printing operation, such one of the type members as has been moved to printing position.

Another object is to provide a key mechanism having two functions, one, to set the respective type member in printing position and the other, to actuate the universal printing member; these two functions being synchronized, so that the printing member contacts with the type member when the type member arrives in approximate printing position.

A further object is to provide a rebound rail for the type member and a flexible section for the type member, so that this member can be moved to print and thereby be slightly flexed and then rebound.

Another object is to provide a universal pressure printing mechanism, subject to actuation by any one of the keys, and comprising a double toggle linkage and a weight member connected to the first one of the toggle linkages so that the actuation of any one of the keys will actuate these mechanisms and impart kinetic energy to the parts thereof, of which, at the end of the stroke, is converted into pressure against the type member.

Another object is to provide a universal pressure printing mechanism and an actuating device therefor, designed to move it from

rest with harmonic motion to thereby overcome its inertia gradually.

A still further object is to mount a weight member in a yielding or flexible manner, so that its rebound action will aid in quickly breaking the toggle for resetting movement.

In the accompanying drawings, only one type member and key action is shown, as being representative of all and the supporting frame work has been eliminated as being immaterial and of any suitable structure.

Figure 1 is a fragmentary side elevation of one of the key actions and the printing device and shows the device in normal position in full lines and in actuated position in dotted lines.

Figure 2 is a detail of the guide plate with the rebound rail.

Figure 3 is a front elevation of an end bar, showing the bevel gear modification of the laterally disposed sector members 3.

The typewriter keys 1 are pivoted on the shaft 2 and the rear extensions thereof carry pins 4 to actuate the sectors 3 by engaging the slots therein. The sectors 3 are mounted on the transverse shaft 4' and actuate with the sector levers 5 pivoted on shaft 6 and these levers carry pins 7 on their upper ends which actuate the type members 9, pivoted on shaft 8', by engaging the slotted extensions 8 thereof. The type members are preferably carried in the radial slots of a segment block (not shown) and are fulcrumed on the curved shaft 8" in the customary manner and the shaft 6, on which the sector levers 5 are pivoted, is mounted and curved in a similar manner.

To provide that the laterally disposed sectors 3 may properly engage the radially extending sectors 5, the upper ends of the sectors 3 are bent to form a section of a bevel gear, as is shown in Figure 3, and as they are of varying heights or lengths, the slot and pin connections between the key extensions and the sectors are positioned to obtain complete connection of the type members.

by the operation of the respective key. The type members are pivoted on the shaft 8' and a thin rod 9 connects the type head 10 with the body portion of the type member. As in this machine the type bars are not actuated to print by kinetic energy, but are merely a convenient means for carrying the type, they can be of light construction and are preferably moved with harmonic motion from normal position and moved with harmonic motion to come to a stop, when positioned for printing. To this end the slotted extensions 8 of the type members are normally disposed with the slots at approximately right angles to the actuating levers 5 and with the pins 7 thereon in the extreme ends of the slots, as shown in Figure 1. By these means, movement of uniform velocity of an actuating lever 5, by its key, will impart gradually accelerated movement to the type bar, until the actuating lever has moved half of its distance and will then impart gradually decelerated movement to the type bar and completely stop it when the lever is at right angles to the slot. By these means the inertia of the type bar at rest is readily overcome and its momentum, when moving fast, is gradually absorbed in a useful manner, as it acts on the actuating lever and helps to move the key down and thereby helps to actuate the printing device.

A guide member 12 is suitably mounted near the platen and two projections 13 thereon, form a guide slot for the rods 9 of the type members to guide them laterally during the last part of the travel. (See Fig. 2.) The guide member 12 also has a projecting rail 12' against which the rod 9 of a type member bears, when the key is in actuated position and in this position the type head 10 is a short distance from the platen 11. Normally, the keys are held in upper position against the rubber bumper 16 by the spring 17 and are subject to operation to assume the position shown in dotted lines, with the upper edge against the bumper 15. Upon operation of a key, the respective type member will be moved with harmonic motion to printing position, that is, it will move with gradually accelerated velocity and then with decelerated velocity until the type member stops in printing position with the type head adjacent to the platen and the rod in the guide slot and against the rebound rail, as is shown in dotted lines. A universal pressure printing mechanism is provided to engage and move to print any type member that has been set in printing position by its key. This printing mechanism comprises a double toggle linkage having a pressure member to engage the type head, and this mechanism is actuated by a universal bail frame which, in turn, is subject to actuation by any one of the keys. The bail frame starts the printing mechanism from rest with harmonic motion to thereby overcome its in-

ertia gradually and obtain a smooth key action. The double toggle linkage is provided so that a sufficient pressure for printing can be obtained from the second toggle linkage and that the first toggle linkage can readily open the second toggle, for quick return movement.

A universal bail frame 18 is provided and carries a transverse plate 19 mounted in the drop links 20 and this plate is subject to actuation by any one of the keys to thereby oscillate the bail frame. In approximately central position of the machine, an upward extending lever 21 is mounted on the bail frame shaft 18' and a link 22 connects this lever to the rear arm of the curved lever 23 pivoted on the stud 24 and held in normal position by the spring 25. The lever 23 is a part of the first toggle linkage provided to engage and actuate the type head for printing operation. A pressure printing member 26 is slidably mounted in the guide plates 27, suitably mounted in the machine and a link 28 connects this member to the lever 29 pivoted on stud 30 and the link 31 connects the lever 29 to the lever 23, thereby completing the linkage. The operation of a key will simultaneously move a type member, as described and actuate the bail frame 18, and the lever 21 thereon, will actuate the lever 23 with gradually accelerated velocity, thereby overcoming the inertia of this mechanism very gradually. The pressure printing member 26 will move rearward to engage the type head 10 of the type member and for an instant press it against the platen for printing operation, thereby flexing the rod 9 of the type member, which therefore will rebound upon resetting movement of the printing member.

The synchronization of the movement of a type member and the pressure printing member is indicated by the dash and dotted lines identified by letters and similar letters indicate the relative positions of the two members at a given phase of the movement. It will be seen that the pressure printing member comes in contact with the type head when the latter has arrived in printing position, and the parts are shown in this position in dotted lines.

To provide means for storing kinetic energy, a weight 32 is mounted on an extension 33 of the link 31 and the quick motion of this weight by the operation of a key, will store kinetic energy therein, which will be available as pressure at the end of the stroke and tend to straighten out the toggle linkage. This weight has the additional function of assisting the spring 25 in the resetting movement of the linkage by its rebound characteristic induced by the flexure of the link extension 33 on which it is mounted.

It is an important consideration in this

type of machine, to maintain a low and balanced key resistance and a quick resetting movement of all of the parts actuated by the keys.

5 In view of this it is undesirable to provide a direct pressure transmission for the keys to the type head or a single toggle mechanism, as such devices would be slow to reset and require a large mass with undesirable inertia. By reason of the double toggle mechanism provided herein, the mass to be moved by the keys is such, that its inertia is not of undesirable magnitude and the provision of a small and flexibly mounted mass in the first toggle linkage for the purpose of storing kinetic energy therein for printing purposes, assures a rebound means and therefore a quick resetting action of the devices.

20 To overcome the inertia of the mass represented by the universal printing mechanism, it is started from rest by the keys with harmonic motion.

25 During the first part of the key stroke, the main resistance is caused by the positioning movement of the type member and as this resistance diminishes, the resistance of the pressure printing linkage increases, thereby balancing the key resistance for the entire key stroke.

30 Variations may be resorted to within the scope of the invention, and portions of the improvements may be used without others.

Having thus described my invention, I claim:

35 1. In a typewriting machine, the combination with a key and a type-member, of meshed gears between the key and said member, and additional means, including lever-arms between the gears and the type-member, 40 actuated by said gears effective upon movement of the key to transmit harmonic motion to the type-member to carry it into typing position.

2. In a typewriting machine, the combination with a type-member and a key, of a key-actuated sector-lever, a second sector-lever to mesh with the same, and additional means, including motion-transmitting arms between the second sector-lever and the type-member, 50 actuated by said sector-lever, for transmitting harmonic motion from the key to said type-member to carry it into typing position.

3. In a typewriting machine, the combination with a key, of a type-member having an elongated opening, a key-actuated sector-lever, a second sector-lever meshed with the key-actuated sector-lever, and a pin carried by the latter engaging said opening for transmitting harmonic motion from the key 55 to said type-member to carry it into typing position.

4. In a typewriting machine, the combination of a platen, a key, a type-member, an extension therefor, a sector-lever engaging said extension to operate said member, a

sector bell-crank to engage and actuate said sector-lever, and key-actuated means for engaging the sector bell-crank effective to move the type-member into typing position.

5. In a typewriting machine, the combination of a type carrying member having a slotted extension; a sector lever carrying a pin adapted to engage the slotted extension of the type member; a sector to engage and actuate the aforesaid sector lever; and a typewriter key having a pin adapted to engage and actuate the sector lever, substantially as shown and described.

6. In a typewriting machine, the combination with a type-member and a key, of a sector-lever for actuating said member, a key-actuated sector-lever engaged therewith to carry said member into typing position in the machine, and a harmonic motion-transmitting device between the type-member and the sector-lever forming a stop for said type-member.

7. In a typewriting machine, the combination of a platen, a rotatable type-member including a resilient bar, a key, a sector-lever for actuating said member, a key-actuated sector-lever engaged therewith to rotate said member to a position near the typing position in the machine, and a printing device effective to flex said bar to press the type-member against the platen for typing.

8. In a typewriting machine, the combination of a series of pivotally mounted front strike type members; a series of typewriter keys adapted to position the type members in printing position; a single printing mechanism, effective to co-operate with all of the type members, said mechanism including a key-actuated toggle device, a longitudinally-movable pressure pin actuated by said toggle device and effective to engage and move the type members to print; a bearing for guiding said pin rectilinearly toward the type members; and connecting means connecting all of the keys with the toggle device and subject to actuation by any one of the keys to actuate the printing mechanism.

9. In a typewriting machine, the combination of a series of type members; a series of keys; a single printing mechanism adapted to co-operate with all of the type members, to engage and move them to print and comprising a toggle linkage controlled at one end by all of the keys and on the other end connected to a second toggle linkage connected to a pressure member, adapted to engage such one of the type members as has been set to printing position and actuate it to print.

10. In a typewriting machine, the combination of a series of type members; a single printing device, adapted to co-operate with all of the type members and comprising a double toggle linkage whereby one toggle linkage actuates the second toggle linkage,

which in turn, actuates the type members to print; and keys to position the type members and simultaneously actuate the printing device.

- 5 11. In a typewriting machine, the combination of a platen, a series of keys, type-members actuated thereby to move near the platen, a printing device to move the type-members against the platen, to print, including a 70

- press the type-members against said platen for typing.
20. In a typewriting machine, the combination with a platen, a series of type-members and a series of keys, of a series of key-actuated motion-transmitting devices including lever-arms, effective for changing the uniform velocity of the keys to a decelerated movement of the members, throughout the last part of their travel, ending in a stop when the same are close to, but not touching, the platen, due to the construction and arrangement of said lever-arms, and a key-actuated printing device, including a pressure member, effective to approach the type-members with a gradually decelerated movement, during the last part of its travel, and to finally press the type-members against the platen for typing. 5 70 75 80
21. In a typewriting machine, the combination of a platen, type-members, including type-heads and flexible rods supporting the same, a series of actuating mechanisms for the same, means included in said mechanisms to actuate the type-members and throughout the last part of their travel to move the same with a decreasing velocity, means effective to stop the type-members near to but not touching said platen, and a key-actuated printing mechanism common to all of said type-members including a pressure-bar effective to flex said type-head rods to press the type-heads against the platen for typing. 25 85
22. In a typewriting machine, the combination with a platen, a series of keys and a series of type-members, of key-actuated means including a sector gearing to transmit motion from the keys to the type-members, and a printing device including a key-actuated toggle-mechanism to actuate said device, a pressure-member and a second toggle-mechanism actuated by the first-named mechanism to engage the pressure-member and press the same against said type-members when the latter are in typing position. 30 90 95
23. In a typewriting machine, the combination with a platen, a key and a type-member, of key-actuated means to transmit motion to the type-member, and a printing device including a key-actuated toggle-mechanism, a pressure-member and a second toggle mechanism actuated by the first-named mechanism to engage the pressure-member to press the same against the type-member when it is in typing position. 50 100 105
24. In a typewriting machine, the combination with a platen, a key and a type-member, of means to transmit motion to the type-member, and a printing device including a pressure-member, a key-actuated toggle-mechanism and a second toggle-mechanism mechanically connected in series relation therewith, actuated by the first-named mechanism to engage the pressure-member and press the same against the type-member when it is in typing position. 30 110 115
25. In a typewriting machine, the combination with a platen, a series of type-members and keys for the same, of means actuated by the keys to bring the type-members near to but not touching said platen, a key-actuated printing device, including a pressure-member, effective to press the type-members against the platen for typing, and a pair of key-actuated toggle-means, including a pivoted support therebetween, effective for giving the type-members and the printing device co-ordinated speeds throughout their entire travel during the typing operation. 15 75 80 85
26. In a typewriting machine, the combination with a platen, a series of type-members and a series of keys, of means connecting the keys and the members for giving the latter harmonic motions to carry them near to the platen, and a key-actuated printing device, including a double system of toggle-linkages, effective to press the members against the platen for typing. 20 85
27. In a typewriting machine, the combination with a platen, a series of type-members and a series of keys, of means connecting the keys and the members for giving the latter harmonic motions to carry them near to the platen, and a key-actuated printing device common to all of the keys and including a double system of toggle-linkages, effective to press the members against the platen for typing. 25 90 95
28. In a typewriting machine, the combination with a platen, a series of type-members and a series of keys, of means connecting the keys and the members for giving the latter harmonic motions to carry them near to the platen, and a key-actuated printing device, including a double system of toggle-linkages and a pressure-bar, effective to press the members against the platen for typing. 30 100 105
29. In a typewriting machine, the combination with a platen, a series of type-members and a series of keys, of means connecting the keys and the members for giving the latter harmonic motions to carry them near to the platen, and a key-actuated printing device, including a plurality of toggle-mechanisms, effective to press the members against the platen for typing. 35 110 115
30. In a typewriting machine, the combination with a platen, a series of type members and a series of keys, of means connecting the keys and the members for giving the latter harmonic motions to carry the members near to the platen, and a key-actuated printing device, having mechanism including a crank and a connecting rod normally positioned on a dead center and effective to be moved therefrom to press the members against the platen for typing, when the members reach their extreme positions resulting from the movements of said means. 40 120 125 130

31. In a typewriting machine, the combination with a platen, a series of type-members and a series of keys, of means connecting the keys and the members for giving the latter harmonic motions to carry them near to the platen and then by said means come to rest, and a key-actuated printing device, including a pair of toggles and a motion-increasing linkage between the same, whereby said device has a motion differing from but synchronized with the motions of the type-members and effective to press the members against the platen for typing.

10 In testimony whereof I affix my signature.

RICHARD V. REPPERT.
